UNITED STATES PATENT OFFICE.

WILLIAM A. BROWN, OF BOISSEVAN, MANITOBA, ASSIGNOR OF ONE HALF
TO BANFIELD CAPRON, OF PARIS, CANADA.

SHEAF-CARRIER.

SPECIFICATION forming part of Letters Patent No. 389,136, dated September 4, 1888.

Application filed August 22, 1887. Serial No. 247,633. (No model.)

To all whom it may concern:

Be it known that I, WILLIAM ALEXANDER BROWN, of the village of Boissevan, in the Turtle Mountain district, in the Province of 5 Manitoba, Canada, farmer, have invented a certain new and useful Improved Sheaf-Carrier, of which the following is a specification.

The object of the invention is to provide a sheaf-carrier which is simple in construction 10 and easily operated so as to effectually dump the sheaves, and which automatically assumes its normal position by gravitation after the load is discharged; and it consists, essentially, of a sheaf-carrying frame having slats or bars 15 composed of two halves jointed together, so that when the sheaf-carrier is tripped to dump the sheaves the front halves of these jointed slats, being pivoted centrally, are caused to tilt by the weight of the load, so as to discharge 20 the sheaves, while the rear halves of these jointed slats at the discharging end of the sheaf-carrier trail along the ground while the sheaves are being discharged. When the load 25 is discharged, the empty sheaf-carrier, owing to the weight of the front portion thereof, automatically assumes its normal position, the bars become straightened out, the rear halves of these hinged bars rising from the ground, and the sheaf-carrier becomes locked in position 30 and ready for a fresh supply of sheaves, as hereinafter more particularly described.

Figure 1 is a perspective view of my improved sheaf-carrier attached to a binder. Fig. 2 is a detail of one of the hinged or jointed 35 slats of the sheaf-carrier. Fig. 3 is a detail of the trip mechanism.

In the drawings like letters of reference indicate similar parts in the different figures.

In Fig. 1, A is a bent bar attached to the binder-frame at the points a and b, the lower end of which, at c, affords a bearing for one end of the sheaf-carrier-supporting rod D, the other end of the rod D being journaled in the bracket E on the journal-bearing C and suitably held in position, the bracket E being rigidly attached to the under side of the discharging-table K of the binder. The cross-bar F of the sheaf-carrier is rigidly secured to the sheaf-carrier-supporting rod D, the two ends thereof being bent 45 upwardly to form standards G and H for the side frame of the bundle-carrier. The stand-

ard H in this figure is shown latched in position between the stop d and the spring-latch e, the details of which are more particularly shown in Fig. 3. f and g are the side and front 55 rails of the sheaf-carrier, adapted to keep the bundles on the sheaf-carrier when discharged from the binder. L is a rock-shaft attached to the frame of the binder, with pedal l on the end of an arm, l', near the driver's seat M. 60 This rock-shaft has another arm, l", on its front end, to which is pivotally attached a link, N, which is hooked to the inner end of the spring-latch e. I I' are the jointed slats, jointed at m, with stop n on the rear ends of the front 65 halves, I', (see Fig. 2,) formed at said joint to keep the slats normally straight, I' being the front half and I the rear half at the discharging end of the sheaf-carrier. The ends of the slats at the discharging end have a slight up- 70 ward curve.

Fig. 2 is a detail of one of these jointed slats of the sheaf-carrier, in which F and F' are sections of the cross-slats, and D section of the sheaf-carrier-supporting rod, to which are rigidly attached the collars O, which are two or 75 three in number, and rigidly connect the cross-bar F of the sheaf-carrier to the sheaf-carrier-supporting rod D, which is adapted to rock in its bearings, so as to tilt the sheaf-carrier and 80 dump the sheaves. The rear half, I, of the slat is jointed to the front half, I', at m, a square shoulder being there formed, and a stop, n, to keep the slat normally straight, and so placed that it will not bend downward. 85

Fig. 3 is a detail of the bracket E, in which is journaled at C one end of the sheaf-carrier-supporting rod D. E' and E' are bent arms formed on the bracket E, and provided with holes o o', through which suitable means, as 90 bolts, are designed to be passed to secure them to the bottom of the table K. These arms are spread, so as to better support the bracket E, which helps to support the sheaf-carrier, the bent bar A and this bracket E bearing the 95 whole weight of the loaded sheaf-carrier. d is a stop forming an elbow, which is bolted to the outer side of the bracket, and e is a spring-latch like an ordinary door-latch, of which e' is the circular spindle, around which is coiled 100 the spiral spring p, one end whereof is attached to the latch end of the spindle, and the other

end bears against the frame-piece P, which is bolted to the inner side of the bracket E. p^2 is the slotted enlarged end of spindle, on which is hooked the link N, which is actuated by the 5 rock-shaft L, so as to withdraw the latch and release the standard H, which is held between the stop and the latch when the sheaf-carrier is in its normal position, as shown by the full lines in Fig. 1.

10 The mode of operation is as follows: When the sheaf-carrier is full of sheaves, which lie lengthwise thereon, the driver releases the sheaf-carrier by pressing his foot on the pedal l of the rock-shaft L. This withdraws the latch 15 e and releases the standard H of the sheaf-carrier frame, and the loaded sheaf-carrier tilts by the weight of the load into the position shown in the dotted lines in Fig. 1, the front halves, I', of the jointed slats tilt to the rear, 20 and the rear halves, I, trail, and the sheaves are rapidly discharged from the sheaf-carrier. When all the sheaves are discharged, the preponderating weight of the front end of the sheaf carrier causes the front end to fall back 25 into its normal position, as shown in the full lines in Fig. 1, and the standard H, passing against the beveled side of the latch e, presses it in, and when past the latch the spring on the latch-spindle causes the latch to shoot out 30 again and lock the sheaf-carrier in its normal position. The falling back into place of the front end of the sheaf-carrier raises the rear halves, I, of the slats from the ground, when they straighten out into line with the front 35 halves, I', of the jointed slats, bearing against the stops n, formed on the front halves, I', as shown in Fig. 2.

What I claim as my invention is—

1. In combination with a binder and the

sheaf-carrier-supporting rod, a sheaf-carrier 40 composed of slats, the slats being halved and jointed together, the front halves being centrally pivoted on said rod and carrying the preponderance of weight of the carrier, whereby when the carrier is discharged it is automatically returned to its normal position and the slats of the rear half straightened out in line with the front halves, the guard-rails f, extended along the sides and head of the carrier, and the standards formed by the bent-up ends 50 of the cross-bar of the carrier, as set forth.

2. The combination, with the bracket E and bent rod A, rigidly attached to the binder and supporting the outer end of the sheaf-carrier-supporting rod D, of the sheaf-carrier-supporting rod D, the sheaf-carrier composed of slats, the slats being halved and the two halves jointed together and the front halves centrally pivoted on said rod, the standard H, stop d on said bracket, spring latch e, link N, and 60 treadle-lever l, connected with said link, substantially as described.

3. The combination, with the base frame of a harvester and the rock-shaft L, journaled thereon, and provided at one end with bent 65 arm l' and pedal l and at the other end with the arm l', of the sheaf-supporting rod D, the bracket E, attached to the binder-table, a stop, d, on said bracket, and a spring latch, a sheaf-carrier, the bracket H on said carrier, held by 70 said latch and stop, and the link N, connecting the spring-latch with the arm l', substantially as and for the purpose specified.

Toronto, July 29, 1887.

W. A. BROWN.

In presence of—

CHARLES C. BALDWIN,
CHAS. H. RICHES.
